S. TAVE,
COVER AND FASTENING MEANS THEREFOR,
APPLICATION FILED JUNE 24, 1919.

1,335,206.

Patented Mar. 30, 1920.

UNITED STATES PATENT OFFICE.

SAMUEL TAVE, OF NEW YORK, N. Y.

COVER AND FASTENING MEANS THEREFOR.

1,335,206.

Specification of Letters Patent. Patented Mar. 30, 1920.

Application filed June 24, 1919. Serial No. 306,467.

To all whom it may concern:

Be it known that I, SAMUEL TAVE, a citizen of the United States, and a resident of the borough of the Bronx, county of the Bronx, city and State of New York, have invented certain new and useful Improvements in Covers and Fastening Means Therefor, of which the following is a specification.

- 10 The present invention relates to improvements in covers and fastening means therefor, and has for an object to provide means by which the cover may be automatically fastened as it is closed, and may be released
- 15 with facility and preferably by the same hand gripping the handle of the cover, so that the other hand will be available for other purposes. The invention will be especially advantageous for ash cans, garbage
- 20 receptacles and the like, where it is desired to have a tight closure and which closure will not be disturbed by turning over of the receptacle or by prowling cats or dogs. A further object of the invention is to provide
- 25 such fastening means which will be very inexpensive and simple to manufacture, and may readily be attached to the types of receptacles at present in use.

With these and other objects in view, an embodiment of my invention is shown in the accompanying drawings and this embodiment will be hereinafter more fully described with reference thereto and the invention will be finally pointed out in the claims.

In the accompanying drawings,

Figure 1 is a side elevation of a garbage receptacle or the like, embodying one form of my invention;

- 40 Fig. 2 is a vertical sectional view with parts broken away, of the cover and the upper part of the can;

Fig. 3 is a front view of a portion of the can and one of the fastening devices provided thereon;

Fig. 4 is a view similar to Fig. 2 showing one of the fastening devices disengaged preparatory to removing the cover; and

- 50 Fig. 5 is a perspective detail view of one of the fastening devices.

Similar reference characters indicate corresponding parts throughout the several figures of the drawings.

Referring to the drawings, the can or

55 other receptacle 10 is provided with a flanged cover 11, the upper edge of the re-

ceptacle being provided with a curled bead or rim 12, while the lower edge of the flange of the cover is provided with a similar curled bead or rim 13, a handle 14 being 60 provided centrally of the cover.

At diametrically opposite points of the flange of the cover there are provided vertical slots 15 and 16 extending to the bead 13 and having their upper ends slightly 65 above the lower extremity of the bead 12 of the receptacle in the engaged position of the cover. The fastening devices at each side are of similar construction, being oppositely arranged as indicated in Fig. 2 by reason 70 of this similarity. The said devices each comprise a back portion 17 of tapering shape having side flanges 18 and 19 bent at right angles thereto, the flange 18 terminating at the base of the portion 17 while 75 the flange 19 is extended into a curved loop portion 20 bent about the bead 13 to constitute a hinge, the lower edge of the portion 17 being curved as at 21 in continuation of the curvature of the loop, the said 80 loop and the said lower edge of the portion 17 being substantially concentric to the bead 13. The back portion 17 is engaged in the slot of the cover and is limited in its swinging movement by engagement of the flanges 85 18 and 19 with the outer and inner surfaces of the said cover, a flat leaf spring 22 secured to the inner side of the flange 19 and bearing upon the inner surface of the cover constantly forcing the device toward its in- 90 wardly projected position, in which position it engages beneath the bead 12 of the receptacle when the cover is engaged therewith. The spring 22 may be secured in a slot 23 provided in the flange 19 or may be 95 riveted, soldered or otherwise suitably secured in place. Other suitable spring means may be provided if desired instead of the leaf spring 22.

In engaging the cover with the receptacle, 100 the fastening devices are forced outwardly by engagement with the bead 12, snapping inwardly into place beneath the said bead as their upper ends pass below the same thereby fastening the cover to the receptacle. 105

Upon the upper side of the cover there is pivotally mounted in a bracket 24, a lever having one arm 25 extending into proximity to the handle 14 and adapted to be pressed 110 by the thumb of the hand engaging the handle, and its other arm 26 bent down-

wardly and forked at its extremity, the portion 17 of the fastening device disposed in the slot 15 and adapted upon outward pressure being exerted thereon by depression of 5 the arm 25 to bear upon the flange 18 swinging the fastening device outwardly and out of locking engagement with the bead 12, thereby enabling the cover to be lifted, the fastening device at the other side being 10 engageable from beneath the bead 12 as the cover at one side is moved above the upper edge of the receptacle, the space between the inner surface of the fastening device and the outer surface of the receptacle being 15 such as to permit swinging movement of the cover. A leaf spring 28 engaged in a slot 29 of the arm 25 adjacent the pivot and bearing upon the top of the cover, constantly forces the said arm 25 upwardly so 20 that the weight of the lever will not tend to disengage the fastening device with which it is connected.

With my improvements, very simple means is provided by which the cover of a 25 receptacle may be effectually fastened and at the same time will permit convenient disengagement of the same with one hand. The device is simple in construction and may be readily attached to the present types of 30 receptacles and covers in use.

I have illustrated and described a preferred and satisfactory embodiment of my invention but it is obvious that changes may be made therein within the spirit and scope 35 thereof as defined in the appended claims.

I claim:

1. The combination of a receptacle having an external projecting abutment in proximity to its upper open end, a cover for 40 closing said receptacle having a dependent flange which shuts over said abutment, said flange having a bead at its lower edge and a vertical slot extending upward from said bead to a point opposite said abutment when 45 the cover is closed, a pivotal oscillatory locking device swung on said bead, extending upward therefrom and adapted to oscillate on said bead and within said slot to engage said abutment, a spring operative to

normally swing said locking device inward, 50 and a releasing lever pivoted to said cover and extending downward between the inner and outer wings of said oscillatory locking device.

2. In combination, a receptacle having a 55 projecting abutment in proximity to its upper open end, a cover having a flange extending below said abutment in the engaged position of said cover with said receptacle, and a plurality of fastening means carried 60 by said flange of said cover and adapted to engage beneath said abutment of said receptacle to lock said cover to said receptacle, one of said fastening means comprising a 65 swinging member, and spring means normally forcing said swinging member inwardly beneath said abutment, and a lever disposed on said cover engaging said swinging member and adapted to be operated to disengage said member from said abutment 70 to permit removal of said cover.

3. In combination, a receptacle having a 75 projecting abutment in proximity to its upper open end, a cover having a flange extending beneath said abutment in the engaged position of said cover with said receptacle, said cover having a curled bead or the like at its lower edge, and a pair of diametrically opposite vertical slots extending 80 above said bead, a pair of fastening devices each comprising a portion engaging said respective slots, side portions bent at right angles thereto, and an extension on one side of said side portions bent about said bead or the like to form a hinge, and a 85 spring mounted upon said side portions at the inner side of said flange of said cover bearing upon the inner side of said flange and yieldably forcing the upper ends of said members into locking relation beneath said 90 abutment, and means mounted on said cover engaging one of said members adapted to operate to disengage said member from said abutment to permit removal of said cover.

In testimony that I claim the foregoing as 95 my invention, I have signed my name hereunder.

SAMUEL TAVE.
